UNITED STATES PATENT OFFICE.

RALPH S. KELSO, OF ROCKFORD, ILLINOIS, ASSIGNOR TO FREE SEWING MACHINE COMPANY, OF ROCKFORD, ILLINOIS, A CORPORATION OF ILLINOIS.

CHAIN CONSTRUCTION.

Application filed December 3, 1925. Serial No. 73,066.

This invention relates to chain constructions and more particularly to a chain drive particularly adapted for use in connection with sewing machines for transmitting power from the needle bar drive shaft to the loop taker shaft.

An important object of the invention is to provide a chain the individual links of which are substantially duplicates of each other and adapted to be readily assembled without the use of special tools.

A still further object is to provide a device of the above mentioned character wherein in the ends of the links are formed conical in shape, the apexes of the conical portions being arranged substantially in contact with each other in end to end relation to permit the similarly formed ends of the next adjacent link to be passed thereover to assemble the links into a completed chain.

A still further object is to provide a chain of the above mentioned character which is adapted to pass about sprocket wheels secured to parallel shafts, alternate links of the chain being curved longitudinally to conform somewhat to the curvature of the sprockets to form a better contact between the chain and sprockets.

A still further object is to provide a novel form of chain structure adapted to provide positive drive means between the needle bar operating shaft and loop taker shaft of a sewing machine.

Other objects and advantages of the invention will become apparent during the course of the following description.

In the drawings I have shown one embodiment of the invention. In this showing:

Figure 1 is a side elevation of a sewing machine, parts being broken away,

Figure 2 is a detail sectional view through the sprockets about which the chain passes, the chain being shown in elevation,

Figure 3 is a detail sectional view through one of the sprockets, and,

Figure 4 is a detail view of a pair of chain links.

Referring to the drawings, the numeral 10 designates the bed plate of a sewing machine having the usual head 11 arranged thereabove to support the upper driving mechanism of the machine. The head is provided with the usual depending reciprocating needle bar 12 adapted to be operated through suitable mechanism from a rotating

needle bar operating shaft 13 provided with the usual hand wheel 14. The shaft 13 is adapted to operate in the bearings 15 carried by the head of the machine. Beneath the bed plate, the machine is provided with a rotating loop taker 16 adapted to be operated by a rotatable shaft 17 supported in bearings 18.

The shaft 13 is provided with a sprocket 19 shown in detail in Figures 2 and 3 of the drawing. The sprocket is adapted to be secured to the shaft 13 to rotate therewith by means of a set screw 20 or other fastening device. The wheel 19 is provided with a substantially cylindrical outer face 21 provided centrally thereof with an annular groove 22 having sprocket teeth 23 projecting outwardly therefrom. These sprocket teeth are formed integral with the wheel 19 and project outwardly beyond the outer face 21 as shown in Figure 2. A similar sprocket

wheel 24 is secured to the shaft 17 as shown in Figure 2, and this sprocket is similarly provided with an outer substantially cylindrical surface 25 having an annular groove 26 arranged substantially centrally thereof. Sprocket teeth 27 similar to the teeth 23 project outwardly from within the groove 26. The teeth 27 are spaced over a distance substantially equal to the teeth 23. The numeral 28 designates a drive chain as a whole comprising links 29 and 30. The links 29 are adapted to pass about the sprocket wheels at right angles to the surfaces thereof, while the links 30 are adapted to lie against the outer surface of the sprocket wheels.

The links 29 and 30 may be formed as duplicates of the same length, or the links 29 may be formed relatively short to bring the adjacent ends of the links 30 passing therethrough close to each other. The links 30 are preferably of a length sufficient to permit the teeth 23 to pass between the ends of the links 29 as will be obvious. In practice I prefer to form the links 30 on an arc of a circle whereby they will lie more flatly against the outer surfaces of the sprocket wheels. The increased surfaces presented between the links 30 and the surfaces of the sprocket wheel formed by curving the links 30 materially reduce the wear on the links 30.

Referring in detail to Figure 4, it will be noted that each link of the chain may be formed of circular wire and this wire is preferably made of steel. Each link is formed with parallel sides and curved ends

as shown, and the ends of the material forming the link preferably terminate centrally of one side thereof. The ends are formed substantially as cones as indicated at 31, and the apexes of the cones are arranged substantially in contact with each other in end to end relation. The angle of the cone may be 90° or slightly less, for a purpose to be described.

10 The operation of the device is as follows: The links of the chain are assembled by placing two links in edge to edge relation with the apexes of the conical ends of the links in registration with each other whereby 15 one link may be slipped into the other one and moved to the solid line position shown in Figure 4. The initial linking position is indicated in dotted lines and it will be apparent that if the angles of the conical portions 20 are 90° or less, successive links easily may be assembled. When curved links 30 are employed, it will be apparent that alternate links of this character are assembled in forming the complete chain. After the chain 25 has been completely assembled, it is placed in position on the sprockets 19 and 24, as will be understood. The shaft 13 then may be revolved by any suitable means such as an electric motor (not shown) to reciprocate the

needle bar in the usual manner. Motion will 30 be transmitted to the shaft 17 by virtue of the chain described, any suitable form of revolving loop taker being employed.

It is to be understood that the form of my 35 invention herewith shown and described is 35 to be taken as a preferred example of the same and that various changes in the shape, size and arrangement of parts may be resorted to without departing from the spirit 40 of the invention or the scope of the subjoined 40 claim.

I claim:

A drive chain comprising a plurality of links, each link comprising a single piece of wire bent to form a resulting link having 45 curved ends, the ends of the material forming each link being arranged intermediate the ends of the link and terminating in substantially conical portions the apexes of which substantially coincide, said conical 50 portions being substantially coaxial and having apex angles not exceeding 90°, each link of the chain being of such length that the adjacent ends of the links connected thereto are spaced a material distance apart. 55

In testimony whereof I affix my signature.

RALPH S. KELSO.
